UNITED STATES PATENT OFFICE

ELMER B. STONE, OF NEW BRITAIN, CONNECTICUT

DESIGN FOR A COMBINATION CATCH AND LOCK

Application filed November 16, 1929. Serial No. 33,476. Term of patent 14 years.

To all whom it may concern:

Be it known that I, ELMER B. STONE, a citizen of the United States, and a resident of New Britain, in the county of Hartford and State of Connecticut, have invented a new, original, and ornamental Design for Combination Catch and Lock, of which the following is a specification, reference being had to the accompanying drawings, forming part thereof, in which—

Figure 1 is a front view of a combination catch and lock showing my new design.

Figure 2 is a side view of the same, and

Figure 3 is a perspective view.

I claim—

The ornamental design for a combination catch and lock, as shown.

ELMER B. STONE.
